UNITED STATES PATENT OFFICE.

ALFRED H. RAYNAL, OF HOBOKEN, NEW JERSEY, ASSIGNOR TO CORNELIUS H. DELAMATER, GEORGE H. ROBINSON, AND WILLIAM DELAMATER, ALL OF NEW YORK, N. Y.

MOLD FOR CASTING TUBE-HEADS.

SPECIFICATION forming part of Letters Patent No. 361,373, dated April 19, 1887.

Application filed February 1, 1887. Serial No. 226,113. (No model.)

To all whom it may concern:

Be it known that I, ALFRED H. RAYNAL, of Hoboken, in the county of Hudson and State of New Jersey, have invented a new and useful Improvement in Molds for Casting Tube Heads or Plates, of which the following is a specification.

My invention may be employed in making plates which have holes or perforations at short intervals in their surfaces, and is particularly useful in making the tube heads or plates of surface-condensers.

According to the ordinary method of making cored tube heads or plates it has been usual to form each core separately and to provide on the pattern core-prints, the separate cores being each set in a separate impression formed in the mold.

The object of my invention is to reduce the expense of forming such tube heads or plates, and also to provide for more accurately sustaining the cores, so that the axes of the several holes or perforations will be truly transverse to the surfaces of the head or plate; and according to my invention I accomplish these results by reducing the expense of forming the cores by reducing the labor upon the pattern and by reducing the labor of placing the cores within the mold.

30 The invention consists in a mold for casting cored tube heads or plates, composed of a lower portion wherein are arranged side by side a series of core-bars, each having formed integral with it a line or row of core projections which extend to the top of said lower portion, and a closed top or cope to which the core projections extend.

In the accompanying drawings I have represented the several steps which are comprised in carrying out my improvement.

Figures 1 and 2 are respectively a side view and an end view of a core-bar having upright and parallel core projections which I employ. Fig. 3 is a plan of such bar, also showing in dotted outline a similar bar arranged in suitable position at the side thereof. Fig. 4 is an edge view of the pattern with its attached core-print. Fig. 5 is a sectional elevation of the mold which has been formed

from the pattern, showing the several core-bars as arranged in place therein; and Fig. 6 is a transverse section of a plate cast in such mold.

Similar letters of reference designate corresponding parts in all the figures.

The finished plate A has in it numerous holes or openings, b, and is intended to serve as a tube head or plate for a surface-condenser or analogous structure, each of said holes being adapted to receive a tube, and, inasmuch as a gland may be employed to compress packing about each tube, I have represented the holes or perforations b as reduced in diameter near one surface of the plate, as shown at b', in order to form the bottom of the packing box.

To produce holes b b' of the form shown in Fig. 6, it is necessary that the several core projections C' (shown in Figs. 1, 2, and 3) should have portions or projections of reduced diameter c at the ends. The cores C' are not separate from each other, as is usual, but they all spring upward from a core-bar, C, and are formed in a core-box integral with said bar. Any desired number of the bars C, with their integral projections C', are made to answer the requirements of the case. The bars may all be made of the same length, and when arranged side by side the core projections C' of adjacent bars should alternate relative to each other in many cases, as is shown in Fig. 3, where I have represented a dotted outline of a second core-bar arranged at the side of the one which is shown in full outline.

It will be observed that a core-bar C, with any number of core-projections C', may be made with far less labor than is necessary to produce an equal number of cylindric cores C' separate from and independent of each other; and this method is also desirable because the cores or core projections C', being formed integral with the bar C, are always maintained in accurate parallel positions. The pattern B, (shown in Fig. 4,) instead of having upon its face a number of separate core-prints equal to the number of holes to be formed in the plate A, has a single core-print, B', the thickness of which is substantially equal to the depth of

the core-bars C, and the dimensions of which are substantially equal to the aggregate dimensions of the necessary number of core-bars when placed side by side, as shown in Fig. 3. 5 In Fig. 5 D D' designate the upper and lower sections of a two-part flask to contain sand for forming a mold of the plate A. After the mold has been formed the core-bars C are placed side by side, as shown in Fig. 5, in the 10 impression left by the core-print B' of the pattern, and they fill the space left by such impression, except, possibly, a little sand may be introduced at the end of each core-bar to fill the spaces formed by the alternate arrangement of the bars one relatively to another, as shown by Fig. 3. When the core-bars C are thus placed in position in the lower section of 15 the mold, the tops of the projections C' are just flush with the surface of that section, and 20 when the cope which is in the upper flask-section, D', is placed in position it makes contact with the top of the core projections C', and the metal may then be poured to fill the mold.

In my mold the cores are all maintained in accurate parallel relation to each other, and, 25 inasmuch as each core projection C' forms an internal part of the long core-bar C, there is no likelihood of the core projections becoming displaced in the operation of pouring.

What I claim as my invention, and desire to 30 secure by Letters Patent, is—

The mold for casting cored tube heads and plates, consisting of a lower portion wherein are arranged side by side a series of core-bars, C, each having formed integral with it a line or 35 row of core projections, C', which extend to the top of said lower portion, and the closed top portion or cope to which the core projections C' extend, substantially as herein described.

ALFRED H. RAYNAL.

Witnesses:

FREDK. HAYNES,
EMIL HERTER.

It is hereby certified that in Letters Patent No. 361,373, granted April 19, 1887, upon the application of Alfred H. Raynal, of Hoboken, New Jersey, for an improvement in "Molds for Casting Tube-Heads," an error appears in the printed specification requiring correction, as follows: On page 2, line 27, the word "internal" should read *integral*; and that the Letters Patent should be read with this correction therein that the same may conform to the record of the case in the Patent Office.

Signed, countersigned, and sealed this 3d day of May, A. D. 1887.
